U.S. Cl. D87—8

FIG. 4

FIG. 5

FIG. 1 is a front perspective view of a combined electrical key and case showing my new design in a partly open condition;

FIG. 2 is a front elevation thereof on a reduced scale in a closed condition;

FIG. 3 is a side elevational view of FIG. 2;

FIG. 4 is a rear elevational view thereof on the same scale as FIG. 2, the case being in a fully open condition revealing the back of the electrical key and the interior of the case cover.

FIG. 5 is a rear elevational view of FIG. 2.

I claim:

The ornamental design for a combined electrical key and case, substantially as shown and described.
